FIXTURE FOR MOUNTING ELECTRIC
WARP STOP MOTIONS

Edwin C. Smith, Providence, R. I., assignor to
Rhode Island Warp Stop Equipment Company,
Portland, Maine, a corporation of Maine

Application September 23, 1931, Serial No. 564,563

8 Claims. (Cl. 139—358)

My invention relates to warp stop motions for looms, and particularly to electrical warp stop motions. Specifically it is a holder for mounting the contact bars or electrodes of an electrical warp stop motion.

The objects of my invention are to provide a holder of sectional construction that can be expanded or contracted in its numerical capacity to accommodate different numbers of electrodes; to provide a means for supporting or mounting the holder, which supporting means can be varied in position relative to the other component parts of the holder to accommodate the point of mounting on the loom and yield maximum range of adjustment for the holder; and to provide means for compensating the accumulated variations and errors that are incident to aggregating numerous abutting elements such as make up my improved holder.

I attain these objects by the means and arrangements of means shown by the accompanying drawings in which:

Fig. 1 is a plan view of my invention as adapted for holding four electrodes;

Fig. 2 is an elevation of the same viewed in the direction indicated by the arrow *a*, Fig. 1;

Fig. 3 is a detail of the base-section 2;

Fig. 4 is a detail of the extension-section 3;

Fig. 5 is a detail of the binder-section 4;

Figs. 6 and 7 show alternative structures of the base-section;

Fig. 8 shows an alternative tightening means for the draw-bolt 5, and alternative thrust construction;

Fig. 9 shows a modification of the binder-section to hold round outside rods or "lease rods", and also thrust rod in sectional form; and

Figs. 10, 11 and 12 show different arrangements and locations of the base-section in the assembled holder.

Similar numerals refer to similar parts throughout the several views and the specification.

In the following specification the assembled device will be termed "holder". The contact or detector bars will be termed "electrodes". The components of the holder which are brought to bear upon the electrodes to clamp them will be known in general as "sections". The different types of section will be known by specific names: "base-section", "extension-section" and "binder-section".

Figs. 1 and 2 show the holder as composed of five sections, the base-section 2, two extension-sections 3, and two binder-sections 4. The extension-sections 3 and the binder-sections 4 are

mounted on the base-section 2 and secured thereto by the draw-bolt 5. Resting upon the bolt 5 are the electrodes 6. By tightening one or both of the nuts 7, the sections are drawn together by the bolt, clamping between them the electrodes 6. 5

The base-section 2 consists of a body 8 and supporting means whereby the holder is mounted in the loom. This supporting means, Figs. 1 and 3, is preferably a hub 9, formed with a hole 10 of either cylindrical or noncylindrical form. A usual mounting in the loom comprises a post 11, Fig. 1, which is secured by any one of well-known means to the loom side. The range of location for this post is often limited and this limitation has distinct bearing upon my invention as will be shown 15 later. The post 11 carries an angle iron 12 which is secured to the post by the set-screw 13. One arm of this angle iron enters the hole 10 of the hub 9. The base-section 2 with its other attached sections can be moved along the angle iron arm 20 and can be secured at any desired position thereon by the set-screw 14.

The faces 15—15, to the planes of which the hole 10 is perpendicular, constitute abutments against which lie the electrodes 6—6 supported 25 by the draw-bolt 5.

Each of the extension-sections 3—3 has two faces 16—16 corresponding to the faces 15—15; and each binder-section has one corresponding face 17. Each section has a hole perpendicular to 30 said faces and parallel to the hole 10 in base-section 2 to receive the draw-bolt 5, to wit, the hole 18 in the base-section 2; the hole 19 in each of the two extension-sections 3—3; and the hole 20 in each of the binder-sections 4—4. In order 35 to insure parallelism of the clamping faces 15, 16 and 17, and their fair-bearing upon the clamped electrodes 6, it is desirable that the faces 17—17 of the binder-sections 4—4 be maintained substantially parallel. This is particularly true 40 where the holder comprises many sections as indicated in Fig. 12. Provision for insuring such parallelism of the faces 17—17 is made in the thrust rod 22 which is carried by the base-section 2 in a hole 23, and extends through the holes 24 45 in each of the extension-sections 3—3, which holes are axially in line with the hole 23 in the base-section 2. Each of the binder-sections 4—4 has a hole 25 which is in line with the holes 23 and 24; and which is tapped to receive the set-screw 26. These set-screws 26—26 bearing against 50 the ends of the thrust rod 22 serve to adjust the spacing of the binder-sections 4 to secure substantial parallelism of their faces 17—17 and insure fair bearings of sections and electrodes, one 55

upon another, and firm clamping of the electrodes 6 when the draw-bolt 5 is tightened.

The base-section 2 and the extension-sections 3 carry sockets 27 and 28, respectively, in which 5 lie center rods 29. These center rods support the warp yarns under weight of the drop wires.

The outside support rods 30—30 are shown in Figs. 1 and 2 as flat bars with rounded edges. They are mounted on the binder-sections 4 by the 10 set-screws 26—26 which are made sufficiently long to receive said rods and the nuts 31—31 by which the rods 30 are secured.

The base-section 2 can be variously located in the assembly as shown diagrammatically in Figs. 15 11 and 12. The importance of this feature arises from conditions previously indicated. There is often little latitude permissible in the location of the post 11 with relation to the loom side 33. Sometimes its distance from the edge of the loom 20 side is less than the length of the assembled holder 32. In placing the electrodes in position in the holder it is necessary to slide them into position endwise as shown in Fig. 10. The operative position of the holder 32 is shown by full lines at C, 25 in which position the loom side 33 blocks the insertion of the electrodes 6. The holder 32 must be in the broken line position D in which position it overlaps or projects, in the direction of the arrow e, past the position of the post 11. By having 30 the base-section 2 located as shown, the position D is possible for the holder 32. Were the post 11 still nearer to the loom side 33 a different location of the base-section 2 might be required as shown in Fig. 11.

Sometimes as many as twelve electrodes are 35 mounted in one loom. In such event, a plurality of base units 2—2 can be employed in each assembly to secure further support on the angle iron 12 and relieve the strain that otherwise would 40 be imposed upon the draw-bolt 5, Fig. 12.

It is in these long extended assemblies that the 45 thrust rod is most important because cumulative errors of dimension accrue to a larger gross error than is the case of numerically smaller aggregations. In the case of holding two electrodes where only a base-section and two binder-sections would 50 complete the assembly, no thrust rod would be needed, if either base-section or binder were thickened at the bottom to compensate for the thickness of the inserted electrodes clamped between their tops.

Fig. 8 shows a holder with a one piece thrust 55 rod 47 extending from binder-section 4 to binder-section 4, but with no provision for adjustment on the binder-sections.

Fig. 9 shows a sectional thrust rod, the base-section 2 having a short rod-section 34 and the extension sections 3 having longer rod-sections 35—35. The binder-sections 36—36 carry set-screws 37—37 same as the set-screws 26—26 in Fig. 2. The purpose of this arrangement is to provide for merchandising and stocking unit-sections, each with its thrust rod unit of appropriate length. Fig. 9 also shows a holder having binder-sections 36 having sockets to receive round outside rods or lease rods 38—38. A wall 39 forms the back of the socket, against which back the ends of the lease rods abut. A U-shaped flange 40 forms the side-walls and bottom of the socket.

Fig. 8 shows alternative means for clamping together the sections of the holder to secure the electrodes. The draw-bolt 41, corresponding to the draw-bolt 5 of Figs. 1 and 2, is fitted at one end with the cam lever or eccentric lever 42, secured to said draw-bolt by the pin 43. The nut

44 at the opposite end of the draw-bolt 41 serves to adjust the clamping tension and the cam lever 42 through co-action of its cam surface 45 and the face 46 of the binder-section 4 (shown, as are the other sections, by broken lines), effects the clamping. 5

Fig. 6 shows an alternative structure of the base-section 2 wherein the hub 48, corresponding to the hub 9 of Fig. 3, is split and is clamped upon the angle iron 12 by the bolt 49. 10

Fig. 7 shows another alternative structure for the base-section 2 for use where the holder is mounted in a slotted bracket 50 instead of on the angle iron 12. The hub 9 of Fig. 3 and hub 47 of Fig. 6, are replaced by a rectangular bracket 51. 15 The bolt 52 passing through the bracket 51 and the slotted bracket 50 serves to secure the base-section 2 at any desired position along said bracket 50.

Obviously other structural modifications and 20 alternatives are available without departing from the spirit of my invention. Therefore, without limiting myself to the precise structures and arrangements thereof described, I claim:

1. In an electrode holder for warp stop motions, 25 the combination with a plurality of electrodes to be held, of a supporting member adapted to be situated between the electrodes of any appropriate pair, clamping-sections cooperating with the supporting member to abut the sides of the electrodes, 30 supporting means engaging said electrodes, which supporting means also serves to hold said clamping-sections to the supporting member and to clamp said electrodes between said member and sections, and means to tighten said supporting 35 and clamping means to clamp and hold the electrodes and hold the sections to the supporting member.

2. In an electrode holder for warp stop motions, 40 the combination with a supporting section and annexed sections, each of said sections having a draw-bolt hole and a thrust rod hole, of binder-sections between which are the aforesaid sections, the binder-sections also having each a hole for a draw-bolt, a draw-bolt extending 45 between all the sections, a thrust rod extending through all the sections but the binder-sections, adjustable means carried by the binder-sections and abutting the thrust rod to adjust the spacing of the binder-sections, and means on the draw-bolt to draw the binder-sections against the thrust rod to close all the sections toward each other to clamp whatever may be between said sections. 50

3. In a device for mounting the electrodes of an electrical warp stop motion in a loom, the combination of a plurality of electrodes, an arm transversely disposed with respect to the electrodes, means to mount the arm on the loom, an electrode clamping section formed to receive said arm to mount it thereon, means to secure the section in different positions on said arm, a plurality of other sections of substantially the same form as the first section, and means independent of the securing means for the first section operative to align said other sections with the first section and to clamp all the sections together to secure the electrodes in place between said sections. 55

4. In an electrode holder for electrical warp stop motions, the combination of a plurality of electrodes, a plurality of sections between which the electrodes are located, a draw bolt extending through said sections below the electrodes to support the latter, means to tighten the draw bolt to clamp the sections upon the electrodes, a thrust 60

rod extending between the end sections and through the intervening sections to limit the extent of approach of the end sections under tightening of the draw bolt, and means to adjust the limiting effect of said thrust rod.

5. In a holder for the electrodes and yarn supporting rods of an electrical stop motion, the combination of a plurality of electrodes, a plurality of yarn-supporting rods, an arm extending transversely of the electrodes and yarn-supporting rods, means to mount the arm on the loom, a plurality of electrode clamping sections disposed between the rods, one of said sections being formed for mounting it in different positions on said arm whereby to adjust the position of the entire holder, said section being variously positioned between the rods to vary the point of attachment of the holder with respect to said rods, means for securing the mounting section in adjusted position on said arm, means for clamping the sections against the electrodes to hold them in place, and means for mounting the yarn-supporting rods aforesaid.

6. In an electrode holder for electrical warp stop motions, the combination of a plurality of electrode clamping sections, one of said sections being formed to mount the holder for adjustment in the direction of the extent of the holder and being also formed to support additional sections to extend the capacity of the holder, the additional sections being mounted adjacent said first

mentioned section which is variously positioned between the ends of the holder and with respect to the other sections, means for securing the first-named section to maintain the assembled holder in adjusted position, and further and independent means for securing the assembled sections together as a unit.

7. In an electrode holder for electrical warp stop motions, the combination of a plurality of electrode clamping sections, one of said sections being formed to adjustably mount the assembled holder on the loom and the other sections being mounted adjacent to the first-named section, means for supporting said other sections adjacent to the first-named section in different locations with respect thereto, and means independent of said last-named supporting means to adjust said assembled holder on the loom.

8. In an electrode holder for electrical warp stop motions, the combination with a plurality of electrodes, of a plurality of clamping sections arranged adjacent the electrodes abutting their opposite sides, each section formed with upper and lower openings extending transversely thereof, means extending through one set of openings to support the sections and clamp them against the sides of the electrodes, and longitudinally adjustable means extending through the other set of openings in the sections for locating their clamping faces in correct parallel relationship.

EDWIN C. SMITH. 30
